JOSÉ JULIÁ, OF BARCELONA, SPAIN

TWISTING MACHINE

Application filed January 5, 1929, Serial No. 330,582, and in Spain October 10, 1928.

Hitherto most of the types of twisting machines for the purpose of twisting threads of textile fibres, present the important disadvantage of not possessing means for voluntary or automatic arresting of the individual spindles, and where such means are provided the application is accompanied by important practical disadvantages.

The invention has among its objects, means 10 of removing these disadvantages, as will be seen from the accompanying description and drawings.

The invention consists of a mechanical combination, by means of which, the individual, voluntary or automatic arrest of the spindles in continuous twisting machines, in which these latter are moved by cords, bands, gears or by friction devices, is accomplished, and also in machines intended for twisting 20 the ends of threads of all textile fibres. The stoppage is effected with complete independence of the spindles in relation to one another, and without the arrest being due to the sliding of any one element upon another, but 25 simply by the disconnection of the spindle from the corresponding driving pulley, the two elements remaining thus from that moment completely independent. By such means the arrest of the spindle is produced 30 automatically on the ending or on the breaking of any one of the threads that are being twisted, in their course from the rack where they are supported in the form of bobbins, balls, or the like until their arrival at the 35 feeding cylinders. The stoppage also occurs when the twisted thread breaks in its course from the feeding cylinders to the spindles. It will be understood that it is possible to 40 effect the arrest of movement at any moment and always with one spindle completely independent of the others.

In all such cases as indicated above, the arrest of movement is effected by the disengagement of the spindle and the corresponding driving pulley, which up to that moment have been connected to rotate together, these two elements being rendered completely independent after the said disengagement, whereby the spindle comes to

rest and the corresponding pulley continues its normal rotary movement.

The automatic arrestment of movement is obtained by the change in position of the thread guides which occurs when the thread breaks or is used up, the said guides falling at that instant to a certain extent and being pushed by small eccentrics of a suitable form, the disengagement of the mechanism being effected by this movement.

When the arrestment of movement is to be produced as a consequence of the exhaustion of the thread supply or rupture of an already twisted thread, that is to say, in the course between the guide cylinders and the spindle, this is effected by the action of a thread guide lever which in its turn releases the stopping mechanism. The lever may also be operated by hand at will, producing the same effect upon the spindle.

The accompanying drawings represent by way of example a construction according to the invention.

Figure 1 is a side elevation partly in section, of mechanism applied to the operation 75 of a bobbin spindle of a twisting machine.

Figure 2 is a detail in perspective of a number of hooks for the admission of the ends or threads corresponding to those to be twisted by each spindle.

Figure 3 is a detail of one of the elements 80 illustrated in Figure 2 indicated separately for sake of clearness.

Figure 4 is a plan of the fork operating lever for effecting its connection.

Figure 5 is a detail on a larger scale of the connecting arrangement with the parts of which it is constituted slightly separated from one another for the sake of clearness.

Figure 6 is a plan of a corresponding part 90 of the arrangement for the engagement of each spindle.

As illustrated in the accompanying drawings a support 1 corresponds to the fixed part of the twisting machine, this support carrying at 2 a rotary spindle which possesses, corresponding to the function of each spindle, an eccentric 3 having an enlarged part 4. At 5 is a cursor arm which consists of two branches 6 and 7. The extremity of the branch 6 car- 100

ries the support 8 of a cylinder 9 serving to conduct the threads which are to be twisted upon each spindle; the said threads pass over another spindle 10 and over a pulley 11 before passing through the guide 12 and arriving at the twisting bobbin 13. These threads are indicated by dot-and-dash lines upon the drawing.

The branch 6 of the cursor arm 5 extends in 10 a downward direction by means of a part 14 which tends to be drawn in an upward direction by the action of a spring 15 connected at one extremity to a hook 16 integrally provided on the part 14 and at the other extremity to a pin 21 on the fixed part 1 of the machine. The part 14 is provided with a head 17 upon which is mounted a step 18 which engages a plate 19 integral with the fixed part 1 of the machine, and the arm 5 may be permitted 20 a small sliding movement as it is supported only by means of projection 20 upon the plate 19.

The branch 7 of the cursor arm 5 comprises at its extremities thread guide rods 21, 22, 23, 25 and 24 (Figure 2) which are made in the form of hooks at their upper part and at their lower part they are fixed in the corresponding catches 25, 26, 27 and 28 which turn freely upon the spindle 29, and hang under their own weights upon the support 30 (Figures 1 and 2) unless the tension of the threads which respectively pass through the hooks of the rods 21, 22, 23 and 24 compels them to become raised. The operation is such that when one 30 or a number of the catches 25, 26, 27 or 28 lie upon the plate 30 they are subjected to the pressure of the projecting part 4 of the eccentric 3, but this projecting part has no action upon them when they are raised by the 35 tension of the threads which pass through their hooks, these threads being those which are to be twisted together.

The fixed plate 19 comprises integral cheeks 31 which support the spindle 32 of a lever 34, 40 35 which at one extremity 34 carries the thread guide 12 and at the other 35 carries an abutment 36 adapted to be controlled in its 45 position by means of the screw 37.

This abutment 36 serves as the support of the rod 38, jointed to the catch 39 (Figure 2), placed upon the same axis as the catches 25-28 so that as long as the support continues, the catch 39 is raised from its seat upon the plate 30 (Figure 1), but if the abutment 36 descends, the rod 38 descending also, the catch 39 falls upon the plate 30 and undergoes pressure from the projecting part 4 of the eccentric 3. This occurs because the rod 38 is joined to the small arm 39 of the 60 catch 39.

The part 14 is connected at its lower end to a double crank 40 which at its lower end is connected to a rod 41 by which it is joined to the angle piece 42 fixed upon the stationary 65 support 43, supporting a bobbin such as 13

and the parts which are hereafter referred to. The rod 41 guides the crank 40, the part 14 and the arm 5 to which is firmly jointed the part 14 in their upward and downward movements. At 44 a fork lever 45 (Figures 70 1 and 4) whose pivotal axis is at 46, is mounted upon the part 40. The other extremity of this lever is connected to a second fork 47 provided with two freely mounted conical rollers 48, 49 (Figure 4) which are supported upon a conical cap 50 (Figure 1), the rollers being indicated in Figure 1 because one part of the fork is removed, and the other part is disposed behind the axis of the bobbin. The cap 50 is able to slide along 80 the axis 54 of the spindle.

Upon the supporting frame 43 on which is mounted the mechanism of the spindles, there is fitted a sleeve 51 which comprises at 85 52 a lubrication box, and is adapted for the reception of a sleeve 53 which carries the spindle 54 of the bobbin. The said sleeve 53 is mounted at its upper part by means of a bearing at 55 leaving a certain amount of annular space in order that the lubricant may rise between it and the sleeve 51; the sleeve 53 itself is provided with perforations such as 53' to allow passage for the said lubricant towards the spindle 54. The spindle 54 of the bobbin is not adjusted exactly 90 with the sleeve 53, that is to say, upon the greater part of their length the parts are not in contact, whereby the usual wear of the bobbin spindle is avoided. This spindle functions normally, although it may be subjected to deviations in relation to the axis of the driving element, by reason of the freedom of movement afforded by the semi-spherical head 55 provided at the upper part of the sleeve 53, and which will adjust itself in the 95 hollow semi-spherical seat in the upper part of the supporting sleeve 51. This action is permissible in view of the fact that the coupling between the spindle and the driving element, for which provision is made in the 100 cylindrical casing 63 of the pulley 56, as hereinafter described, is elastic, as that is to say, the said coupling renders oscillation of the 105 spindle of no importance.

61 and 62 are small springs which are supported on inclined planes provided at the lower part of the sleeve 53. These springs act to balance the sleeve 53 in position and to ensure the satisfactory seating of the head 55 upon its seat and to absorb the vibrations 110 which may be produced in the spindle.

The pulley 56 which engages with the endless belt which drives the spindle is shown in section. This pulley is mounted on races of ball bearings 57 and 58, their cones 59 and 60 being fixed firmly to the sleeve 51. The pulley 56 is fixed firmly to a cylindrical casing 63 formed on the interior with recesses such as 64, which engage mutually with projections on a gear wheel 65; the wheel turns 120 125 130

freely on the axle 54 of the spindle and carries projections such as 66 (Figure 6) situated on its two faces, these projections being of cork, or of any other elastic material, adapted to establish a good frictional contact. A wheel or disc 67 (Figures 1 and 5) is firmly fixed to the axle 54, and contains orifices such as 68, 69, 70, which are penetrated freely by rods such as 71, 72, and 73, fixed in another disc 74 which is able to slide right along the same spindle 54. The rods (71, 72, 73 etc.) pass freely through the central orifice 75 (Figure 6) of the gear wheel 65.

15 On the rods 71, 72, 73 (Figures 1 and 5) are mounted compression springs such as 76, 78 (Figure 5) which are supported at one end by the disc 67 and at the other by pins such as 79, 80, which cross the rods 71, 72, 73 at their upper parts. The action of these springs is such that the discs 67 and 74 together with the gear wheel, form a coupling, strengthened by the elastic pieces such as 66 (Figure 6). This coupling has its parts disengaged, producing the disengagement of gears, on depression of the cap 50, because this cap, depressing the heads of the rods 71, 72, 73 overcomes the action of the springs 76, 77, 78, causing the depression of the disc 74; and the contact or coupling pressure of the joint or the gear wheel 65 with the disc 67 and 74, diminishing, the rotation of the said gear wheel remains free and independent of the axle 54 of the spindle, the coupling of 85 the casing 63 and the pulley 56 still remaining free on the axle 54 of the spindle.

The mechanism functions as follows: The threads which are to be twisted on each bobbin being passed through the hooks corresponding to the rods 21, 22, 23 and 24 (Figures 1 and 2) as well as on to the conducting cylinders 9 and 10 and the pulley 11 (Figure 1) as indicated by the dot and dash line 81, next cross the thread guide 12 and are joined to 45 the bobbin 13. If in the working of the machine one of the threads is broken, the corresponding guide e. g. 21 becomes free of the thrust or tension of the thread and the catch 25 falls under its own weight on to the support 30. The jutting embossment 4 of the eccentric 3 pushes the said catch 25 and displaces the arm 5 from right to left, the step 18 falling out of its supports with the plate 19, so that the arm 14 rises under the action 55 of the spring 15, and the lever 45, because of the joint 44 and of its pivot 46, moves so that the conical rollers 48, 49 (Figure 4) depress the cap 50 (Figures 1 and 5) upon which, the axle 54 of the spindle is put out of gear by the bearing of the casing 63 and hence the pulley 56, which receives motion from the endless belt as has been explained is consequently stopped. At the same time, following the displacement of the arm 5, the cylinder 9 breaks contact with the roller 10, from

which it receives its motion and consequently the supports of the spindle 13 remain suspended.

If the already twisted thread becomes broken between the roller 10 and the spindle 13, the arm of the lever 34 will be freed from the tension of the said thread, and the lever 34, 35, which when functioning normally is in equilibrium, loses this equilibrium, the abutment 36 descending. Then the rod 38 remaining free, the catch 39 (Figure 5) would fail on the part 30, being pushed by the projection 4 (Figure 1) of the eccentric 3, so that they would produce as we have said, the higher displacement of the arm 5, the disconnection of the step 18 from the part 19, the functioning of the lever 45 and the pushing of the cap 50 by the conical rollers 48, 49 (Figure 4) the mechanism functioning as described above and thus the spindle 13 (Figure 1) is stopped.

Once the broken threads have been mended the workman replaces the arm 5 into its working position and the machine continues normally.

The disengagement of the above described gear, which as has been seen is automatic, is effected in order to obtain the stoppage of each bobbin of the machine at will and to do which it is only necessary to move by hand the arm 5 or the lever 34, 32 and 35.

The lubrication of the casing 52 and of the axle of the spindle, takes place by means of a reserve chamber 82 (Figure 1) which communicates by a tube 83, bent into the bottom of the said box 52. The lubricant besides rising up the axle 54, the sleeve 53, and the casing 51 naturally, rises still more under the action of centrifugal force developed by the rotation of the axle 54 of the spindle and so arrives at the cap 55 and from there, by the openings existing between the various parts of the pulley 56, the sleeve 51, and the casing 64, the said lubricant arrives at the ball bearings 57, 58. The tube 83 stands inside the vessel 82 and receives the lubricant by means of a wick 84 in a fine jet in spite of which the lubricant is accomplished perfectly.

I claim:—

1. A driving mechanism for the spindles of twisting machines for twisting threads, permitting freedom of lateral inclination to the said spindle, comprising a supporting sleeve for the said spindle, a driving element rotatably mounted upon the said supporting sleeve, a bearing sleeve in which the spindle is rotatably mounted, said bearing sleeve being capable of lateral inclination in the said supporting sleeve, and a coupling between the said spindle and the said driving element comprising coupling plates partly carried by said spindle and partly engaged by said driving element, the said engagement permitting inclination of the axis of the spindle relatively to the axis of

the driving element, substantially as hereinbefore described.

2. A driving mechanism for the spindles of twisting machines for twisting threads, 5 permitting freedom of lateral inclination to the said spindle, comprising a supporting sleeve for the said spindle, a driving element rotatably mounted upon the said supporting sleeve, a bearing sleeve in which the 10 spindle is rotatably mounted, said bearing sleeve being capable of lateral inclination in the said supporting sleeve, and a coupling between the said spindle and the said driving element comprising a disc fixed to the 15 spindle, a disc slidably mounted upon the said spindle, rods carried by the said slideable disc which penetrate holes in the first disc, the said discs being concentric with the driving member which is provided of annular form, a driven member slidably engaged with the said driving member and capable of inclination relatively thereto, the said driven member being disposed between the discs upon the said spindle, springs concentric with and engaging the said rods for pressing the two discs relatively towards each other to engage the said driven member, and a slideable member mounted on the 20 said spindle adjacent the ends of the said rods to apply pressure upon the said rods when the discs are required to be disengaged against the action of the said springs, substantially as hereinbefore described.

3. A driving mechanism for the spindles 35 of twisting machines for twisting threads according to claim 2, having a cylindrical driving member with the inner surface formed with a plurality of recesses in a direction parallel with the axis, and a driven 40 member formed on its periphery with a plurality of teeth to engage the recesses of the said driving member, the said recesses and teeth being so formed as to permit relative inclination of the axes of the driving and driven members in operation of the driving mechanism, substantially as hereinbefore described.

4. A driving mechanism for the spindles 50 of twisting machines for twisting threads according to claim 2, having a cylindrical driving member with the inner surface formed with a plurality of recesses in a direction parallel with the axis and a driven member formed on its periphery with a plurality of teeth to engage the recesses of the 55 said driving member, the said recesses and teeth being of a form to permit relative inclination of the axes of the driving and driven members, and said driven member being provided with a plurality of elastic projections to engage the discs mounted upon the spindle, substantially as hereinbefore described.

5. A driving mechanism for the spindles 65 of twisting machines for twisting threads,

permitting freedom of lateral inclination to the said spindle, comprising a supporting sleeve for the said spindle, a driving element rotatably mounted upon the said supporting sleeve, a bearing sleeve in which the spindle is rotatably mounted, the said bearing sleeve being closed at the lower end and formed with a semi-spherical head which is received in a semi-spherical hollow in the upper end of the supporting sleeve, the said bearing sleeve fitting loosely within the said supporting sleeve so that its axis may be inclined relatively to the axis of the supporting sleeve, and a coupling between the said spindle and the said driving element comprising coupling plates partly carried by said spindle and partly engaged by said driving element, the said engagement permitting inclination to the axis of the spindle relatively to the axis of the driving element, substantially as hereinbefore described.

6. A driving mechanism for the spindles of twisting machines for twisting threads, permitting freedom of lateral inclination to the said spindle, comprising a supporting sleeve for the said spindle, ball bearings exterior to the said supporting sleeve, a driving element supported by the said ball bearings, a bearing sleeve for the said spindle closed at the lower end and formed with a semi-spherical head, said bearing sleeve being concentrically disposed and loosely fitted within the said supporting sleeve with the semi-spherical head received into a semi-spherical hollow of the said supporting sleeve, an annular extension of the said driving member concentric with the spindle, and a coupling between the said spindle and the said extension comprising coupling plates partly carried by the said spindle and partly engaged with the said extension of the driving element, the said engagement and the fitting of the bearing sleeve within the supporting sleeve permitting inclination of the axis of the spindle relatively to the axis of the driving element, substantially as hereinbefore described.

7. A driving mechanism for the spindles of twisting machines for twisting threads, permitting freedom of lateral inclination to the said spindle, comprising a supporting sleeve for the said spindle, a driving element rotatably mounted upon the said supporting sleeve, a bearing sleeve for the said spindle closed at the lower end and formed with a semi-spherical head for reception in a semi-spherical hollow at the upper end of the supporting sleeve, the said bearing sleeve being loose within the said supporting sleeve, springs seated within the said supporting sleeve and engaging inclined seatings upon the bearing sleeve so disposed that the springs tend to press the bearing sleeve downwardly within the supporting sleeve while permitting lateral inclination of the

said bearing sleeve relatively to the said supporting sleeve, and a coupling between the said spindle and the said driving element comprising coupling plates partly carried by
5 the said spindle and partly engaged by the said driving element, the said engagement permitting inclination of the axis of the spindle relatively to the axis of the driving element, substantially as hereinbefore de-
10 scribed.
